FIG.-2

NATHANIEL E. LOOMIS Inventor

By his Attorney A. A. Straw

UNITED STATES PATENT OFFICE

NATHANIEL E. LOOMIS, OF WESTFIELD, NEW JERSEY, ASSIGNOR TO STANDARD OIL DEVELOPMENT COMPANY, A CORPORATION OF DELAWARE

METHOD AND APPARATUS FOR CRACKING HYDROCARBONS

Application filed March 3, 1927. Serial No. 172,259.

This invention relates to improvements in the cracking of petroleum oils and the like. In a preferred embodiment, the invention comprises heating the oil to a cracking temperature under pressure in a coil, then passing the oil through a series of enlarged thermally-insulated reaction chambers, wherein it undergoes further cracking under pressure while largely in vapor phase. The oil and/or oil vapor is heated in its passage between the units of the apparatus so as to maintain an efficient cracking temperature. The product is withdrawn from the last chamber of the series, and the vapors are fractionated and condensed.

The invention will be fully understood from the following description, read in connection with the accompanying drawings, in which

Fig. 1 is a diagrammatic side elevation of equipment suitable for practicing the method; and

Fig. 2 is a top plan view of the same equipment, partly broken away.

Referring to the drawings, reference numeral 1 denotes a pipe arranged to supply oil to be cracked to an elongated passageway or cracking coil 2 mounted in a heating chamber 3. The coil may be composed of about 1600 ft. of 4" pipe, preferably arranged for a successive counter-current and concurrent flow of oil with respect to hot gases, as shown. The coil 2 discharges through pipe 4 into a heating conduit 5, immersed in a lead bath 6, or other means for maintaining a uniform high temperature. The lead bath or salt bath, such as that of sodium nitrite is set in a furnace 7 connected by a flue 8 to supply hot gases to the cracking coil 2.

From the heating conduit 5 the oil passes through a pipe 9 into the lower portion of an enlarged chamber or soaking drum 10. This is heavily lagged or otherwise protected against any substantial loss of heat. The drum may be a heavy steel cylinder usually not larger than about 3' in diameter by 20' in height. However, smaller drums may be used with advantage, especially where a considerable number are connected in series.

Three 3' by 20' drums are ordinarily sufficient for best results.

The oil emerges from the top of the drum 10 through pipe 11 and enters a second heating conduit 12. It passes through this conduit and pipe 13 into a second drum 14, similar to that just described. From drum 14 the oil emerges through pipe 15, which leads to a third heating conduit 16, and thence the oil flows through pipe 17 to a third drum 18. Each of the drums is provided with a draw-off line 19 near its bottom, and valves 20 are arranged in these draw-off lines.

The cracked product is taken off from the third drum 18 through pipe 21 to the lower chamber of a bubble tower or other fractionating means 22. Pressure is relieved at valve 23 in the pipe 21. The bubble tower is provided with the usual cooling coil 24, collecting pan 25 with draw-off pipe 25', and bell cap plates 26 above the inlet pipe 21. The vapors from the tower pass through pipe 27, having a pressure control valve 27', and are condensed and collected in any suitable manner. Condensate formed in the tower is drawn off through pipes 25' and 28.

The pipes conveying the oil between the several cracking units are preferably heat-insulated, but the bath 6 can be depended upon to make up the heat losses from uninsulated pipes.

The operation of the improved method in a preferred form is as follows: Kerosene, light gas oil, or other stock suitable for cracking in vapor phase, is passed through coil 2, at a rate of about 3,000 gallons per hour. The stock is raised in the coil to a temperature at which incipient cracking takes place and is in condition to be readily vaporized when passed into the reaction chamber or soaking drum 10. The temperature of the oil emerging from the cracking coil 2 is preferably about 900° F., and the pressure about 350-400 lbs. per square inch. Before entering drum 10, the oil passes through the heating conduit 5, in which its temperature is raised about 50° F. It is discharged through pipe 9 into the lower portion of drum 10 at about 950° F.

I have found that this increment of heat

is necessary for efficient vapor phase cracking. It cannot be imparted to the oil in the cracking coil 2 without serious danger of hard coke formation in the coil tubes. This danger is not met in heating conduit 5. The high rate of heat transfer between the molten metal or other fused material of the bath 6 and the conduit makes it possible to heat the oil very quickly to the desired temperature without substantial formation of coke.

10 The time of heating in the cracking coil may be one minute or less, and the time of digestion may be from about one to five minutes in each drum. The period of travel through conduit 5 may be only a few seconds.

15 These times may be considerably varied, depending upon the stock, the amount of conversion desired, and other factors.

The oil passes through pipe 11 and heating conduit 12 to the next drum of the series. 20 It will be understood that the oil is mostly vaporized, but some liquid oil may be present. Any heat lost is supplied in the conduit 12 and the oil is raised to an efficient conversion temperature, as above described.

25 Similarly, the oil passes from the second drum through pipe 15 and heating coil 16 to the third drum 18. Pressure is released at valve 23 and the products from drum 18 are delivered into the lower chamber of the bubble tower 22. The tower may be operated under pressure, but lower than that in the cracking zones, for example, 60 lbs. per square inch. Gasoline and kerosene are taken off through line 27 to condensing means, not shown. Gas oil collected in pan 25 is suitable for recycling 30 through the system, or for other uses.

35 The invention is particularly adapted for vapor phase cracking. The difficulty has been to maintain the temperature of the vapors at a point to give a high cracking rate without the use of extremely large cracking chambers for prolonging the cracking period. By heating as described herein, the oil is efficiently cracked.

40 To prevent building up of liquid in the drums, the heavy oil collecting at their bottoms may be drawn off intermittently or continuously through the pipes 19. The invention is not restricted to use in vapor phase 45 operations, and where liquid phase, or semi-liquid phase cracking is desired, the drums may be allowed to become more or less full of liquid.

50 Various changes may be made in the preferred method and equipment described, within the scope of the appended claims, in which it is my intention to claim all novelty inherent in the invention as broadly as the prior 55 art permits.

I claim:

1. The improvement in the process of cracking relatively low-boiling petroleum oils, which comprises heating the oil to a 60 cracking and vaporizing temperature about

900° F. under a pressure of about 350-400 lbs. per square inch in an elongated passage-way, further heating the oil to about 950° F. in a conduit immersed in a molten bath, then digesting the oil largely in vapor phase in a thermally insulated zone wherein some loss of heat occurs, passing the oil from the digestion zone through a heating conduit in which any loss of heat is made up, and then into another digestion stage, and recovering the 75 cracked product.

2. In the cracking of hydrocarbons in the vapor phase, the method that comprises heating a stream of the hydrocarbons to an incipient vapor phase cracking temperature under 80 a pressure of 350-400 pounds per square inch, further heating the hydrocarbons to an efficient vapor phase cracking temperature by passing them through an elongated passage immersed in a fused bath, passing the 85 heated hydrocarbons to a thermally insulated zone of relatively large cross-sectional area whereby cracking takes place, and withdrawing the cracked hydrocarbons.

3. Apparatus for the cracking of oil and comprising a cracking coil, means for supplying hot gases to heat the coil, a fused bath, a conduit immersed therein, a connection for passing oil from the cracking coil to the conduit, a plurality of digestion chambers connected in series, and a conduit immersed in the fused bath to heat the oil between each chamber.

In testimony that I claim the foregoing as my invention, I affix my signature.

NATHANIEL E. LOOMIS.
